UNITED STATES PATENT OFFICE

WILLIAM C. HIERING, OF NEWARK, NEW JERSEY, ASSIGNOR TO J. E. MERGOTT COMPANY, OF NEWARK, NEW JERSEY, A CORPORATION OF DELAWARE

BAG-FRAME FACING

Application filed June 24, 1927. Serial No. 201,168.

This invention relates to the frames of hand-bags, purses, and like containers, particularly such as are used by women to receive minor toilet articles, money, handkerchiefs, and the like, and in which ornamentation is a desirable feature.

While such frames have previously been constructed of celluloid, phenolic condensate products and material of a similar nature, such frames are subject to distortion, due to climatic changes and variations in temperature, are not well adapted to receive fastening means and furnish frail connections at their hinged joints.

15 It is therefore one object of the present invention to provide a metallic frame faced on its outer sides exposed to view with a covering or veneer of celluloid or the like which may be colored in accordance with fancy.

20 A further feature is in the provision of adequate securing means for connecting the outer ornamental layer or facing to the metal portions of the frame.

25 These and other advantageous objects are accomplished by the novel construction and combination of parts hereinafter described and shown in the accompanying drawings, forming a material portion of this description and in which:—

30 Figure 1 is a top plan view showing a conventional type of hand-bag frame as made in accordance with the invention.

Figure 2 is a side elevational view of the same, parts being broken away to show the 35 construction.

Figure 3 is an enlarged fragmentary sectional view, illustrating the first step in securing fasteners as to the facing.

Figure 4 is a similar view of the same, 40 showing the second step employed.

Figure 5 is a fragmentary inside edge view showing the facing as secured to one of the metal side frames.

Figure 6 is a partial inside elevational view 45 of one of the facing members.

Figure 7 is a fragmentary side view of a facing, showing a modification of the connecting member as inserted therein.

Figure 8 is a transverse sectional view 50 taken on line 8—8 of Figure 7.

Figure 9 is a fragmentary side view showing a modified type of facing.

Figure 10 is a transverse sectional view taken on line 10—10 of Figure 9.

Figure 11 is a view similar to Figure 6, but 55 showing an adaptation of another type of facing fastener.

Figure 12 is a fragmentary side elevational view of the metal support frame as used in connection with Figure 11.

Figure 13 is a transverse sectional view of 60 the metal frame and its facing in a completed or united condition.

In the fabrication of these frames, as shown in Figures 1 and 2, the metal portions 15 and 16 are of channel shape cross-section, bent into the usual U-shape and connected in the ordinary manner at their lower extending ends by hinge joints 17 and brazed and otherwise secured on the upper elements of both frame members 15 and 16 are rigid clips 18 and 18'; their inner adjacent ends being raised and bent to support spherical elements 19 and 19' which co-act to retain the two side members in clamped relation.

In each of the channel frame sides, in the outer elements of the channels, are a series 75 of small circular perforations 20, the frames otherwise being of ordinary appearance and construction throughout.

The ornamental cover facings are either moulded into shape or cut from a sheet of the selected material, the profile being in accordance with the shape of the frame sides and their edges inwardly curved so that no rough 80 corners occur.

The facings 21 are provided with circular recesses 22 formed in register with the axes of the openings 20, and extend partially into the facings from their inner sides which are 85 eventually placed in juxtaposition to the frame sides.

The elements by which these facings are secured to the frame sides, consist of hollow posts 23 suited to pass through the openings 90 20, and having at one end a conical flange 24, adapted to enter the recesses 22 as shown best in Figure 3.

The process of securely embedding the conical flange of the fastener is illustrated in 100

Figure 4 and consists merely of flattening the conical portion after insertion within the recess, such operation forcing the edges of the flange into the material, causing them to become firmly embedded therein and without distortion to the facing.

The third step consists merely of inserting the tubular elements 23 into the openings in the side frame and thereafter upsetting the 10 ends as shown in Figure 5 thus firmly riveting the facings to the frames.

In the modification shown in Figures 7 and 8, a tubular post or rivet 25, is used, the same having an annularly flanged flat head 26, 15 suited to tightly fit within the recesses 22, and a washer-like element 27 is passed over the stems 25 filling a counter-bored cavity 28 in the casing, this washer being secured by cement so as to hold the post firmly, the same 20 being afterwards passed through the openings in the bag-frame and clinched or riveted on the inner side of the adjacent portion of the channel as before.

In the modification shown in Figure 9 two 25 layers of facings are used, the outer, designated by the numeral 30, being of pearl or like substance and is provided with a circular recess 32 in which are set the heads 33 of tubular rivets 34 which pass through openings of appropriate diameter in the inner facing 31, of celluloid, this inner facing being 30 used for the purpose of providing a cushion effect for the pearl facing and may be colored as desired.

35 Figures 11 to 13 inclusive show an outer facing 35 in which is embedded the heads 36 of studs 37 provided with enlarged heads 38 which project a definite distance from the inner side of the facing.

40 The side frames 15' are provided with circular openings 39, through which the heads 38 of the stud may freely pass. The stems 37 of the studs engaged in slots 40 extending outwardly from the openings 39, in the direction 45 of the connecting elements between the channel members of the frame sides.

It will be seen in these views that the facings are interchangeably engaged and removable at will. Although the foregoing is generally descriptive of the invention, it will be 50 apparent that minor changes may be made in the construction without the exercise of invention or conflicting with the scope of the claims herewith appended to.

55 Having thus described my inventions, what I claim as new and desire to secure by Letters Patent, is:—

1. In combination with a bag frame member, a condensate product facing provided 60 with a recess on the inner side thereof, a concealed member for securing said frame member and facing together comprising a cylindrical stem provided with a conical head adapted to be inserted into the recesses, the 65 circumferential edge portion of said conical

head being adapted to be spread in the recess to cut into and become embedded in the portion of the facing forming the lowermost wall of the recess to rigidly hold the conical head in place, said stem flattened out to engage with and have holding engagement with the bag frame member to secure the facing thereto.

2. In combination with metallic bag frame members, non-metallic facings for said members, said facings having recesses on the inner sides thereof, securing members provided with conical heads adapted to be spread within said recesses to be securely embedded therein, and stems on said members adapted to engage with the bag frame members to secure the facings thereto.

This specification signed and witnessed this 23rd day of June, 1927.

WILLIAM C. HIERING.
